US0D1015837S

(12) **United States Design Patent** (10) **Patent No.:** **US D1,015,837 S**
(45) **Date of Patent:** **** Feb. 27, 2024**

(54) **WRENCH**

(71) Applicant: **Hong Ann Tool Industries Co., Ltd.**,
Taichung (TW)

(72) Inventor: **Cheng-Wei Su**, Taichung (TW)

(73) Assignee: **Hong Ann Tool Industries Co., Ltd.**,
Taichung (TW)

(**) Term: **15 Years**

(21) Appl. No.: **29/804,292**

(22) Filed: **Aug. 19, 2021**

(51) **LOC (14) Cl.** **08-05**

(52) **U.S. Cl.**

USPC **D8/21**; D8/17

CLAIM

The ornamental design for a wrench, as shown and described.

DESCRIPTION

FIG. 1 is a perspective view of a wrench showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a cross-sectional view taken along line 9-9 in FIG. 3 thereof; and,

FIG. 10 is a cross-sectional view taken along line 10-10 in FIG. 3.

The shaded surfaces and the solid lines represent the claimed portions of the design.

The broken lines depict portions of the wrench in which the design is embodied that are not considered part of the claimed design.

1 Claim, 9 Drawing Sheets
